MACHINE FOR SPLICING PAPER

Russell Q. Triquet, Kalamazoo, Mich., assignor to Kalamazoo Vegetable Parchment Co., Parchment, Mich.

Application December 6, 1954, Serial No. 473,167

18 Claims. (Cl. 242—58.2)

This invention relates to improvements in a machine for splicing paper. The principal objects of this invention are:

First, to provide an improved machine for splicing the leading end of a roll of paper stock to the trailing end of a preceding roll of stock so that the paper stock of the rolls can be advanced as a continuous web through a paper treating machine for coating, converting or otherwise working on the web of paper.

Second, to provide a splicing machine which is easily controlled by the operator to make the splice at the desired point on the leading web of paper.

Third, to provide a splicing machine in which the bearings for supporting the core shafts of paper stock rolls are at all times fixedly and adjustably mounted on the machine so that it is unnecessary to disconnect and reconnect the bearings to the machine in order to mount each new roll on the machine.

Fourth, to provide a novel form of driving mechanism and controls for driving the drive roll of a splicing machine and for rotating the new roll of stock at the same peripheral speed as the drive roll for effectively completing a splice.

Fifth, to provide a novel support for the drive roll of a splicing machine which yieldably presents the drive roll to the surface of the new roll of stock for making the splice and which automatically disconnects the drive to the stock roll advancing mechanism after the stock roll is advanced to bear against the drive roll.

Other objects and advantages of the invention will be apparent from a consideration of the following description and claims. The drawings of which there are five sheets illustrates a highly practical form of the invention.

Fig. 1 is a plan view of the splicing machine with new and old rolls of the stock operatively mounted on the machine, the view having a portion of the transverse width thereof broken away.

Fig. 2 is a fragmentary longitudinal cross sectional view through the machine taken on the plane of the line 2—2 in Figs. 1 and 3 with portions of the stock rolls omitted to illustrate details of the machine.

Fig. 3 is a fragmentary transverse cross sectional view taken along the plane of the line 3—3 in Fig. 2.

Fig. 4 is a fragmentary longitudinal cross sectional view similar to Fig. 2 but showing the mechanism adjusted to make a splice.

Fig. 5 is a fragmentary longitudinal cross sectional view similar to Fig. 4 but showing the structure adjusted to bring the new stock roll up to speed prior to making the splice.

Fig. 6 is a fragmentary view taken transversely through the drive roll support along the plane of the line 6—6 in Fig. 3 to illustrate the supporting structure for the drive roll and the automatic cut-out switch for stopping the stock roll advancing mechanism.

Fig. 7 is a fragmentary cross sectional view taken along the plane of the line 7—7 in Fig. 3 and illustrates in detail the support for the stock roll starting mechanism.

2

Fig. 8 is a fragmentary cross sectional view through one of the stock rolls supporting bearings and advancing slides taken along the plane of the line 8—8 in Fig. 3.

Fig. 9 is a detailed cross sectional view through one of the bearing supports taken along the plane of the line 9—9 in Fig. 8.

Fig. 10 is a fragmentary cross sectional view through one of the slideways and bearing advance nuts taken along the same plane as line 9.

It is common practice in the paper making art to carry out coating or treating operations such as waxing or parchmentizing or finishing as continuous operations on a web of suitable stock paper and the stock paper is supplied in separate rolls so that the trailing end of one roll of stock must be spliced to the leading end of a second roll of stock. It is further old to make these splices while the machine is operating and without stopping the continuous delivery of the paper stock to the treating or coating machine. In making this splice without stopping the delivery of the stock web a replacement roll of stock is torn to provide a tapered tongue or tab on the leading end of the replacement stock and this tab is temporarily secured to the outside of the replacement roll and coated with adhesive on the outside of the tab. The replacement roll is then rotated at the same peripheral speed as the lineal speed of the web advancing from the old roll of stock and the replacement roll is advanced into contact with the moving web near the end of the old roll. The adhesive tab on the new roll is picked up by and adheres to the old web and is advanced with it into the treating machine so that the tapered tongue feeds into the machine along with the old web until the full width of the new roll of stock is threaded into the machine along with the trailing end of the web on the old roll of stock. In order to minimize the length of the stock that is of double thickness the web of the old roll may be cut as soon as the full width of the new roll of stock is threaded into the machine.

The features of the present machine which perform the foregoing splicing operation include a frame 1 having relatively heavy and rigid side members 2. Supported along the tops of the side members is a first set of slideway forming members 3—3 having flattened slideways 4 on their top and forming a trough like opening or recess 5. A second set of slideway forming members 6 are secured at the tops of the side frames and along the inner sides thereof below the level of the slideway members 3. The slideway members 6 have similar slide surfaces 7 on the top and form upwardly opening U-shaped recesses 8.

A first pair of slide members 9 are slidably supported on the slide surfaces 4 of the slide members 3. The slides 9 receive and support upwardly opening transversely extending bearings 10 for rotatably supporting the transversely extending core shaft 11 of a first paper stock roll 12. The other set of slideway members 6 support similar slides 13 that support bearings 14 for rotatably supporting a second core shaft 15 of a second roll of stock 16.

Extending longitudinally through the channel recesses 5 in the first slideway members 3 are elongated screw elements 17 rotatably supported in bearing plates 18 at the end of the frame. A similar set of screw elements 19 are positioned in the recesses 8 in the second set of slideway members 6. Each of the screw elements 17 and 19 carries a travel nut 20 having a squared upper side 21 (see Figs. 8—10) that fits into a notch 22 in the underside of the slide members 9 and 13 mounted on the slideways. Rotation of the screw elements thus functions to move the slide members and the bearings supported thereby along the slideways.

The forward ends of the screw elements 17 are con-

nected through gear boxes 23 (see Fig. 1) with a cross shaft 24 and a drive motor 25 for simultaneously moving core shaft 11 forward or backward along the frame. The forward ends of the screw elements 19 are connected through gear boxes 26 with a second cross shaft 27 and a motor 28 for similarly moving the second core shaft 15. With reference to Fig. 3 it will be noted that the bearings 10 and 14 and the core shafts 11 and 15 supported thereby are in clearing relation so that the shafts can be moved forwardly and rearwardly past each other on the machine as desired. The yoke 29 carrying a screw 30 and friction brake block 31 on one of the bearing supports is readily removable to permit advancement of the core shafts.

Mounted on the inside of each side member 2 of the frame is a support arm 32 pivotally supported in generally upright position on the shouldered bolts 33. The upper swinging ends of the support arms 32 rotatably and movably support a cross drive shaft 34 having a drive roll 35 connected thereto midway between the side members of the frames. One end of the shaft 34 projects through holes provided therefor in the side member of the frame and carries a sprocket 36 adapted to be driven by the chains 37 at the same speed as the paper treating machine 38 with which the splicing machine is associated. Movement of the support arms 32 on the pivot bolts 33 is limited as will be described so relatively small holes 39 in the side frame permit sufficient movement of the shaft 34. The driven roll 35 performs the dual function of both guiding the web of paper from the roll 16 and also pulling or feeding off the web from the roll. If other paper pulling or feeding means are provided the roll 35 may function solely as a paper guide and need not rotate.

Rotatably mounted on the drive shaft 34 between the support means 32 and the ends of the drive roll 35 are a pair of depending hanger arms 40. Desirably bearings 41 are retained in recesses in the hanger arms by end plates 42 (see Fig. 7) so that the hanger arms are freely rotatable on the drive shaft 34. The lower swinging ends of the hanger arms rotatably support a starter roll shaft 43 which thus extends in spaced parallel relation to the drive shaft 34 and drive roll 35. One of the hanger arms 40 carries an idler gear 44 that is meshed with a drive gear 45 keyed to the drive shaft and a driven gear 46 keyed to the starter shaft. The starter shaft thus rotates in the same direction and desirably at the same speed as the drive shaft. The starter shaft 43 carries transversely spaced starter rolls 47 for engagement with the surface of a new stock roll as will be described.

The forward sides of the hanger arms 40 are provided with brackets 48 to which the piston rods 49 of pneumatic cylinders 50 are pivotally attached. The forward ends of the cylinders 50 are pivotally connected at 51 (see Fig. 2) to a forward member of the frame 1. As will be seen from a comparison of Figs. 2 and 5 extension of the piston rod 49 will swing the starter rolls 47 upwardly into driving engagement with the new roll of stock 12.

The weight of the starter shaft 43 and starter rolls 47 is relatively heavy and this weight is supported in part by the action of the piston rod 49. The weight is also applied through the hanger arms 40 to the drive shaft 34 at a point rearwardly from the pivot pins 33 so that the drive shaft 34 is weight biased rearwardly on the support arms 32. In order to limit rearward rotation of the support arms 32 the side members 2 of the frame are provided with stop blocks 52 that engage the support arms to locate the drive shaft in the desired normal operating position.

The web of paper from the first or old roll of stock 16 is trained around the drive roll 35. In order to provide a driving engagement between the web and the drive roll there is provided a pressure roll 53 having oppositely spiraled rubber ribs 54 on the surface. The pressure roll

is supported at its ends on crank arms 55 pivotally mounted on the side members 2 of the frame. The pivot 56 which supports the crank arm may also support a guide roll 57. Brackets 58 mounted on the side frame carry pneumatic cylinders or bellows 59 having piston rods 60 connected to the cranks 55 for pressing the pressure rolls against the drive roll.

The web of stock from the first roll 16 is trained around the drive roll from a position near the forward ends of the slideway members as is best shown in Fig. 2. This leaves space for the mounting of a second stock roll 12 between the side members and rearwardly of the drive roll while the stock is running out from the first roll as will be understood. During running out of the first roll the pressure of the pressure roll 53 is adjusted by control of the cylinder 59 and a control element 61 for regulating the pressure in the cylinder is indicated in Fig. 1. Concurrently the new roll of stock 12 with its splice tab 62 prepared and coated with adhesive as at 63 is advanced forwardly to adjacent the drive roll by actuation of the motor 25 through its control buttons 64.

Prior to bringing the new roll 12 into contact with the drive roll the operator actuates the pneumatic cylinder 50 by operation of the control 65 to raise the starter roll 47 into driving engagement with the surface of the new roll as appears in Fig. 5. This starts the new roll rotating in its bearings after which the new roll is moved forwardly until it contacts the driving roll as shown in Fig. 4. The splice connection is made in the well known automatic manner and as soon as the splice is complete the old web may be cut by a knife 66 supported by the bell cranks 67 on the sides of the frame. Pneumatic cylinders 68 operate the knife and are controlled by the control element 69 on the control panel.

In the event that the operator does not stop forward motion of the new roll 12 at the correct time the pressure of the new stock roll 12 on the drive roll 35 will move the support arms 32 away from the stop blocks 52. One of the stop blocks carries a safety switch 70 (see Fig. 6) that opens when the drive roll is moved forwardly. The switch 70 is connected in the energizing circuit of the motors 25 and 28 to automatically stop further forward feeding of the new stock roll. The circuit for driving the motors rearwardly is independent of the switch 70 so that the screws can be reversed to back the roll of stock away from the drive roll.

It will be noted that either the bearings 10 and the slide members 9 or the bearings 14 and the slide members 13 are operative to advance the new roll of stock to an exhausted roll supported on the other set of bearings and slide members. After the splice is complete the exhausted roll and its core shaft are removed from the splicing machine and the then empty slide members, either 9 or 13 can be retracted by screws to the opposite side of the full roll of stock to ready the machine for another new roll of stock. As each new roll decreases in size until it can clear the drive roll 35 it is moved forwardly to make room for the succeeding roll. Desirably limit switches 71 are mounted at the ends of the slideways 4 and 7 for actuation by the slide members 9 and 13 and connected in the energizing circuits of the motors 25 and 28 to prevent over travel of the slide members.

Having thus described the invention what is claimed to be new and desired to be secured by Letters Patent is:

1. A paper splicing machine comprising, a frame having spaced side members, a first pair of slide ways on said side members, bearing block slidable in said ways and adapted to removably support the core shaft of a roll of paper with the roll disposed between said side members, a second set of slide ways on said side members and positioned alongside of and below said first set of ways, other bearing blocks slidable in said second ways and adapted to support a second core shaft of a second roll of paper disposed between said side members, drive screws connected to move said bearing blocks along said ways, the

bearing blocks on each set of ways being disposed in clearing relation to the blocks on the other set of ways and a shaft carried thereby, motors connected to reversely rotate said screws, support arms pivoted on said side members and supporting a drive roll at their swinging upper ends, drive means connected to drive said drive roll, cranks pivotally supported on said side members and swingably and rotatably supporting a pressure roll under said drive roll, a fluid pressure operated piston connected to said cranks to urge said pressure roll into coacting relation with said drive roll, hanger arms pivotally mounted on the ends of said support arms adjacent to the ends of said drive roll and depending below the drive roll, a starter roll rotatably and swingably supported between said hanger arms and weight biasing said drive roll and support arms in one direction, idler gears carried by said hanger arms and drivingly engaged between said drive roll and said starter roll to drive said starter roll in the same direction as said drive roll, a fluid actuated cylinder pivotally connected to said frame and having its piston pivotally connected to said hanger arms to adjustably support said starter roll, a stop limiting movement of said support arms under the biasing force of said starter roll, control means including manually operable control elements connected to reversely drive said motors, other control means connected to separately actuate said piston and said cylinder, a knife positioned to cut the web delivered to said drive roll from a roll on one of said sets of bearing blocks, a control connected to actuate said knife, and a switch on said frame positioned to be closed by one of said support arms when the arm is against said stop and to be opened when said arm moves away from said stop, said switch being connected in series with the power supply to said motors to stop forward drive of said motors when said support arms move away from said stop.

2. A paper splicing machine comprising, a frame having spaced side members, a first pair of slide ways on said side members, bearing blocks slideable in said ways and adapted to removably support the core shaft of a roll of paper with the roll disposed between said side members, a second set of slide ways on said side members, other bearing blocks slideable in said second ways and adapted to support a second core shaft of a second roll of paper disposed between said side members, drive screws connected to move said bearing blocks along said ways, the bearing blocks on each set of ways being disposed in clearing relation to the blocks on the other set of ways and a shaft carried thereby, motors connected to reversely rotate said screws, support arms pivoted on said side members and supporting a drive roll at their swinging ends, drive means connected to drive said drive roll, cranks pivotally supported on said side members and swingably and rotatably supporting a pressure roll under said drive roll, a fluid pressure operated piston connected to said cranks to urge said pressure roll into coacting relation with said drive roll, hanger arms pivotally mounted on the ends of said support arms adjacent to the ends of said drive roll and depending below the drive roll, a starter roll rotatably and swingably supported between said hanger arms and weight biasing said drive roll and support arms in one direction, means carried by said hanger arms and drivingly engaged between said drive roll and said starter roll to drive said starter roll in the same direction as said drive roll, a fluid actuated cylinder pivotally connected to said frame and having its piston pivotally connected to said hanger arms to adjustably support said starter roll, a stop limiting movement of said support arms under the biasing force of said starter roll, control means including manually operable control elements connected to reversely drive said motors, other control means connected to separately actuate said piston and said cylinder, and a switch on said frame positioned to be closed by one of said support arms when the arm is against said stop and connected in series with the power supply to said motors

to stop forward drive of said motors when said support arms move away from said stop.

3. A paper splicing machine comprising, a frame having spaced side members, a first pair of slide ways on said side member, bearing blocks slideable in said ways and adapted to removably support the core shaft of a roll of paper with the roll disposed between said side members, a second set of slide ways on said side members, other bearing blocks slideable in said second ways and adapted to support a second core shaft of a second roll of paper disposed between said side members, drive screws connected to move said bearing blocks along said ways, the bearing blocks on each set of ways being disposed in clearing relation to the blocks on the other set of ways and a shaft carried thereby, motors connected to reversely rotate said screws, support arms pivoted on said side members and supporting a drive roll at their swinging ends, drive means connected to drive said drive roll, cranks pivotally supported on said side members and swingably and rotatably supporting a pressure roll under said drive roll, a fluid pressure operated piston connected to said cranks to urge said pressure roll into coacting relation with said drive roll, hanger arms pivotally mounted on the ends of said support arms adjacent to the ends of said drive roll and depending below the drive roll, a starter roll rotatably and swingably supported between said hanger arms and weight biasing said drive roll and support arms in one direction, means carried by one of said hanger arms and drivingly engaged between said drive roll and said starter roll to drive said starter roll in the same direction as said drive roll, a fluid actuated cylinder pivotally connected to said frame and having its piston pivotally connected to said hanger arms to adjustably support said starter roll, and a stop limiting movement of said support arms under the biasing force of said starter roll.

4. A paper splicing machine comprising, a frame having spaced side members, a first pair of slide ways on said side members, bearing blocks slideable in said ways and adapted to removably support the core shaft of a roll of paper with the roll disposed between said side members, a second set of slide ways on said side members, other bearing blocks slideable in said second ways and adapted to support a second core shaft of a second roll of paper disposed between said side members, means connected to move said bearing blocks along said ways, the bearing blocks on each set of ways being disposed in clearing relation to the blocks on the other set of ways and a shaft carried thereby, support arms pivoted on said side members and supporting a drive roll at their swinging ends, drive means connected to drive said drive roll, means swingably and rotatably supporting a pressure roll under said drive roll, means to urge said pressure roll into coacting relation with said drive roll, hanger arms pivotally mounted on the ends of said support arms adjacent to the ends of said drive roll and depending below the drive roll, a starter roll rotatably and swingably supported between said hanger arms and weight biasing said drive roll and support arms in one direction, means carried by one of said hanger arms and drivingly engaged between said drive roll and said starter roll to drive said starter roll in the same direction as said drive roll, means pivotally connected to said hanger arms to adjustably support said starter roll, and a stop limiting movement of said support arms under the biasing force of said starter roll.

5. A paper splicing machine comprising, a frame having spaced side members, a first pair of slide ways on said side members, bearing blocks slideable in said ways and adapted to removably support the core shaft of a roll of paper with the roll disposed between said side members, a second set of slide ways on said side members and positioned alongside of and below said first set of ways, other bearing blocks slideable in said second ways and adapted to support a second core shaft of a second roll of paper disposed between said side members, drive means

connected to move said bearing blocks along said ways, the bearing blocks on each set of ways being disposed in clearing relation to the blocks on the other set of ways and a shaft carried thereby, motors connected to reversely operate said drive means, support arms pivoted on said side members and supporting a drive roll at their swinging ends, a second drive means connected to drive said drive roll, means swingably and rotatably supporting a pressure roll under said drive roll, a fluid pressure operated device connected to urge said pressure roll into coacting relation with said drive roll, hanger arms pivotally mounted on the ends of said support arms adjacent to the ends of said drive roll and depending below the drive roll, a starter roll rotatably and swingably supported between said hanger arms and weight biasing said drive roll and support arms in one direction, means carried by one of said hanger arms and drivingly engaged between said drive roll and said starter roll to drive said starter roll in the same direction as said drive roll, lift means connected between said frame and said hanger arms to adjustably support said starter roll, a stop limiting movement of said support arms under the biasing force of said starter roll, control means including manually operable control elements connected to reversely drive said motors, other control means connected to separately actuate said pressure operated device and said lift means, and a switch on said frame positioned to be closed by one of said support arms when the arm is against said stop and to be opened when said arm moves away from said stop, said switch being connected in series with the power supply to said motors to stop said motors when said support arms move away from said stop.

6. A paper splicing machine comprising, a frame having spaced side members, a first pair of slide ways on said side members, bearing blocks slidable in said ways and adapted to removably support the core shaft of a roll of paper with the roll disposed between said side members, a second set of slide ways on said side members and positioned alongside of and below said first set of ways, other bearing blocks slidable in said second ways and adapted to support a second core shaft of a second roll of paper disposed between said side members, drive means connected to move said bearing blocks along said ways, the bearing blocks on each set of ways being disposed in clearing relation to the blocks on the other set of ways and a shaft carried thereby, motors connected to reversely operate said drive means, support arms pivoted on said side members and supporting a drive roll at their swinging ends, a second drive means connected to drive said drive roll, means swingably and rotatably supporting a pressure roll under said drive roll, a fluid pressure operated device connected to urge said pressure roll into coacting relation with said drive roll, hanger arms pivotally mounted on the ends of said support arms adjacent to the ends of said drive roll and depending therefrom, a starter roll rotatably and swingably supported between said hanger arms and weight biasing said drive roll and support arms in one direction, means carried by one of said hanger arms and drivingly engaged between said drive roll and said starter roll to drive said starter roll in the same direction as said drive roll, lift means connected between said frame and said hanger arms to adjustably support said starter roll, a stop limiting movement of said support arms under the biasing force of said starter roll, and a switch on said frame positioned to be closed by one of said support arms and to be opened when said arm moves away from said stop, said switch being connected in series with the power supply to said motors to stop said motors when said support arms move away from said stop.

7. A paper splicing machine comprising, a frame having spaced side members, a first pair of slide ways on said side members, bearing blocks slidable in said ways and adapted to removably support the core shaft of a roll of paper with the roll disposed between said side

members, a second set of slide ways on said side members, other bearing blocks slidable in said second ways and adapted to support a second core shaft of a second roll of paper disposed between said side members, drive screws connected to move said bearing blocks along said ways, the bearing blocks on each set of ways being disposed in clearing relation to the blocks on the other set of ways and a shaft carried thereby, motors connected to reversely rotate said screws, a drive roll rotatably and laterally shiftably mounted between said side members, drive means connected to drive said drive roll, a pressure roll positioned in coacting relation with said drive roll, hanger arms pivotally mounted adjacent the ends of said drive roll and depending therebelow, a starter roll rotatably and swingably supported between said hanger arms, means carried by said hanger arms and drivingly engaged between said drive roll and said starter roll to drive said starter roll in the same direction as said drive roll, means connected to said frame and said hanger arms to adjustably move said starter roll into contact with a roll of stock paper supported on one of said slide ways, a stop limiting lateral movement of said feed roll, control means including manually operable control elements connected to reversely drive said motors, other control means connected to actuate said means for moving said starter roll, and a switch on said frame positioned to be closed by said drive roll in one position and opened when said drive roll is shifted laterally by pressure thereon by a roll of paper stock and connected in series with the power supply to said motors to stop said motors.

8. A paper splicing machine comprising, a frame having spaced side members, a first pair of slide ways on said side members, bearing blocks slidable in said ways and adapted to removably support the core shaft of a roll of paper with the roll disposed between said side members, a second set of slide ways on said side members, other bearing blocks slidable in said second ways and adapted to support a second core shaft of a second roll of paper disposed between said side members, drive means connected to move said bearing blocks along said ways, the bearing blocks on each set of ways being disposed in clearing relation to the blocks on the other set of ways and a shaft carried thereby, motors connected to reversely operate said drive means, a drive roll rotatably and laterally shiftably mounted between said side members, drive means connected to drive said drive roll, a pressure roll positioned in coacting relation with said drive roll, hanger arms pivotally mounted adjacent the ends of said drive roll and depending therebelow, a starter roll rotatably and swingably supported between said hanger arms, and means carried by said hanger arms and drivingly engaged between said drive roll and said starter roll to drive said starter roll in the same direction as said drive roll.

9. A paper splicing machine comprising, a frame having spaced side members, a first pair of slide ways on said side members, bearing blocks slidable in said ways and adapted to removably support the core shaft of a roll of paper with the roll disposed between said side members, a second set of slide ways on said side members parallel to said first set, other bearing blocks slidable in said second ways and adapted to support a second core shaft of a second roll of paper disposed between said side members, drive screws connected to move said bearing blocks along said ways, the bearing blocks on each set of ways being disposed in clearing relation to the blocks on the other set of ways and a shaft carried thereby, motors connected to reversely rotate said screws, coacting paper drive and pressure rolls mounted between said side members below said ways with the drive roll positioned in the path of a full roll of paper advanced along either set of ways, a starter roll rotatably and swingably supported between said side members, means connected to drive said starter roll in the same direction as said drive roll, and manual-

ly operable control means connected to selectively and reversibly actuate said motors to drive said screw means to move said bearings on said ways.

10. A paper splicing machine comprising, a frame having spaced side members, a first pair of slide ways on said side members, bearing blocks slideable in said ways and adapted to removably support the core shaft of a roll of paper with the roll disposed between said side members, a second set of slide ways on said side members parallel to said first set, other bearing blocks slideable in said second ways and adapted to support a second core shaft of a second roll of paper disposed between said side members, means connected to move said bearing members along said ways, the bearing blocks on each set of ways being disposed in clearing relation to the blocks on the other set of ways and a shaft carried thereby, motors connected to reversely drive said means, coacting paper drive and pressure rolls mounted between said side members below said ways with the drive roll positioned in the path of a full roll of paper advanced along either set of ways, and manually operable control means connected to selectively and reversibly actuate said motors to drive said screw means to move said bearings on said ways.

11. A paper splicing machine comprising, a frame having spaced side members, a first pair of slide ways on said side members, bearing blocks slideable in said ways and adapted to removably support the core shaft of a roll of paper with the roll disposed between said side members, a second set of slide ways on said side members parallel to said first set, other bearing blocks slideable in said second ways and adapted to support a second core shaft of a second roll of paper disposed between said side members, means connected to move said bearing members along said ways, the bearing blocks on each set of ways being disposed in clearing relation to the blocks on the other set of ways and a shaft carried thereby, and a roll disposed between said side members at a point between the ends of said slideways to deliver the outgoing web from a roll of paper supported on either of said slideways and adapted to be engaged by the surface of a thick roll of paper stock supported and advanced by the blocks on either pair of slide ways but in clearing relation to a thick roll of paper stock advanced by the blocks on the other pair of slideways.

12. A paper splicing machine comprising, a frame having spaced side members, a first pair of slide ways on said side members, bearing blocks slideable in said ways and adapted to removably support the core shaft of a roll of paper with the roll disposed between said side members, a second set of slide ways on said side members parallel to said first set, other bearing blocks slideable in said second ways and adapted to support a second core shaft of a second roll of paper disposed between said side members, means connected to move said bearing members along said ways, the bearing blocks on each set of ways being disposed in clearing relation to the blocks on the other set of ways and a shaft carried thereby, and a paper guide disposed between said side members at a point between the ends of said slideways to deliver the outgoing web from a roll of paper supported on either of said slideways and adapted to be engaged by the surface of a thick roll of paper stock supported and advanced by the blocks on either pair of slide ways but in clearing relation to a thick roll of paper stock advanced by the blocks the other pair of slideways.

13. A paper splicing machine comprising, a frame having spaced side members, means for removably supporting a core shaft of a roll of paper stock between said side members and for advancing said shaft and roll of stock transversely along said frame, support arms pivotally supported on said side members, a paper feeding and guiding roll supported on the swinging ends of said support arms and positioned above the pivots there-

of in the path of a roll of stock advanced by said advancing means, means for driving said guiding roll, hanger arms pivotally supported about the axis of said guiding roll adjacent the ends thereof, a starter roll rotatably mounted on the swinging ends of said hanger arms, means for adjustably supporting said hanger arms in laterally projecting position with respect to said guiding roll, means carried by one of said hanger arms and drivingly engaged with said guiding roll and said starter roll to rotate said starter roll in the same direction as said guiding roll, means connected to said hanger arms and operable to raise said hanger arms to press said starter roll against a roll of stock on said core shaft supporting means, a stop on said frame engageable with one of said support arms to limit rotation of the support arms on their pivots under the influence of the weight of said starter roll, and a switch mounted on said frame and biased to closed position by movement of said support arms into engagement with said stop, said switch being connected with said means for advancing said core shaft to stop advancing motion of the roll of stock when said guiding roll is lifted away from its stop.

14. A paper splicing machine comprising, a frame having spaced side members, means for removably supporting a core shaft of a roll of paper stock between said side members and for advancing said shaft and roll of stock transversely along said frame, support arms pivotally supported on said side members, a paper guiding roll supported on the swinging ends of said support arms and positioned above the pivots thereof in the path of a roll of stock advanced by said advancing means, hanger arms pivotally supported about the axis of said guiding roll adjacent the ends thereof, a starter roll rotatably mounted on the swinging ends of said hanger arms, means for adjustably supporting said hanger arms in laterally projecting position with respect to said guiding roll, means carried by one of said hanger arms and drivingly engaged with said guiding roll to rotate said starter roll, means connected to said hanger arms and operable to raise said hanger arms to press said starter roll against a roll of stock on said core shaft supporting means, a stop on said frame engageable with one of said support arms to limit rotation of the support arms on their pivots under the influence of the weight of said starter roll, and a switch mounted on said frame and biased to closer position by movement of said support arms into engagement with said stop, said switch being connected with said means for advancing said core shaft to stop advancing motion of the roll of stock when said guiding roll is lifted away from its stop.

15. A paper splicing machine comprising, a frame having spaced side members, means for removably supporting a core shaft of a roll of paper stock between said side members and for advancing said shaft and roll of stock transversely along said frame, support arms pivotally supported on said side members, a paper guide supported on the swinging ends of said support arms and positioned above the pivots thereof in the path of a roll of stock advanced by said advancing means, hanger arms pivotally supported by said guide adjacent the ends thereof, a starter roll rotatably mounted on the swinging ends of said hanger arms, means for adjustably supporting said hanger arms in laterally projecting position with respect to said guiding roll and for raising said starter roll into contact with a stock roll, means carried by one of said hanger arms and drivingly engaged with said starter roll to rotate said starter roll in the same direction as said guiding roll, a stop on said frame engageable with one of said support arms to limit rotation of the support arms on their pivots under the influence of the weight of said starter roll, and a switch mounted on said frame and biased to closed position by movement of said support arms into engagement with said stop, said switch being connected with said means for advancing said core shaft,

to stop advancing motion of the roll of stock when said guiding roll is lifted away from its stop.

16. A paper splicing machine comprising, a frame having spaced side members, means for removably supporting a core shaft of a roll of paper stock between said side members and for advancing said shaft and roll of stock transversely along said frame, a paper guide yieldably supported between said side members to have a web from said stock roll trained thereover and positioned in the path of a roll of stock advanced by said advancing means, hanger arms pivotally supported adjacent the end of said guide, a starter roll rotatably mounted on the swinging ends of said hanger arms, means carried by one of said hanger arms and drivingly engaged with said starter roll to rotate said starter roll, means connected to said hanger arms and operable to raise said hanger arms to press said starter roll against a roll of stock on said core shaft supporting means, and a switch mounted on said frame and controlled by movement of said paper guide, said switch being connected with said means for advancing said core shaft to stop advancing motion of the roll of stock when said guide is shifted by said stock roll.

17. A structure of the class described comprising pairs

of laterally spaced parallel slide ways, transversely aligned pairs of slides slidable on said ways and provided with upwardly facing open shaft bearings, means for translating the slides of each pair of slides simultaneously on their ways, the ways and slides being arranged so that pairs of slides may be translated to and fro on their ways in passing relation to the other pair of slides.

18. A structure of the class described comprising pairs of laterally spaced parallel slide ways, the ways of one pair being disposed in parallel longitudinally overlapping relation with the ways of the other pair, transversely aligned pairs of slides slidable on said ways and adapted to removably support a shaft, means for translating the slides of each pair of slides simultaneously on their ways, the ways and slides being arranged so that the pairs of slides may be translated to and fro on their ways in passing relation to the other pair of slides.
